UNITED STATES PATENT OFFICE.

ALBERT L. ABBOTT, OF YOUNGSTOWN, OHIO, ASSIGNOR TO OHIO AUTOMATIC SPRINKLER COMPANY, OF YOUNGSTOWN, OHIO, A CORPORATION OF OHIO.

SPRINKLER-HEAD-TESTING DEVICE.

Application filed May 21, 1920. Serial No. 383,911.

To all whom it may concern:

Be it known that I, ALBERT LITTLE ABBOTT, of Youngstown, Mahoning County, State of Ohio, have made a certain new and useful Invention relating to Sprinkler-Head-Testing Devices, of which the following is a specification, taken in connection with the accompanying drawing, which forms part of the same.

10 This invention relates to devices for submitting automatic sprinkler heads or other devices to hydraulic test and for conveniently and effectively gripping and releasing the sprinkler heads in connection therewith.

15 The testing device may advantageously comprise one or more gripping jaws which may be threaded or otherwise formed to cooperate with the threaded stem or other convenient portion of each of the automatic

20 sprinkler heads or devices to be tested. These jaws may be pivotally mounted and normally spring retracted, if desired, and by providing them with rotary cam actuating devices two or more gripping jaws

25 may simultaneously engage and grip the sprinkler head stem and exert a centering action thereon, if desired. It is advantageous to have a plunger formed with a yielding or elastic socket or packing to

30 engage the stem of the sprinkler head and this plunger which may have a constricted fluid passage therethrough may be slidably mounted in the casing to which the jaws are secured and may be automatically forced

35 upward to make a tight effective joint with the sprinkler head when the water is turned on to place the head under the testing pressure of three to five hundred pounds per square inch more or less. This forces up the plunger so that tight contact with the head

40 is made and leakage prevented and after the testing fluid is shut off the plunger may be released and retracted if desired by a releasing spring in the casing.

45 In the illustrative embodiment of this invention shown in the drawing which is a vertical sectional view the supply pipe 5 communicating with any desired valve mechanism for turning on and off the high

50 pressure testing fluid, may, for instance, be screwed to the threaded stem 4 of the base 1 which may have a screw joint 28 with the casing 2. This casing may be formed with the integral brackets 15 to

55 support the desired number of gripping

jaws through which may extend the jaw pivots 13, 14 on each side of the casing so as to support these gripping jaws 18 which may be formed with threaded portions 19 to properly cooperate with the threaded 60 stem or connecting portion 21 of the sprinkler arm 20 or other device to be tested which may of course have any desired construction. These gripping jaws which may have integral depending or angularly arranged jaw arms 11, 12, may, if desired, be spring retracted, for which purpose the springs 17 may be arranged to extend around the lower part of these jaw arms and be coiled or twisted around the jaw pivots 14 65 before having their ends secured to any suitable portion of the jaw brackets, as, for instance, the spring retainer pins 16. In this way the two or more jaw arms are normally retracted by such spring action so 70 that the connected gripping jaws 18 are normally withdrawn so as to permit the insertion or removal of a sprinkler head. The position of these gripping jaws is, however, preferably controlled by a rotary 75 cam 9 which may be mounted within an annular recess 26 between the base 1 and connected casing of the device. When the cam is turned in the direction of the arrow as by the projecting handle 10 thereon the 80 depending ends of the jaw arms are forced outward which gives a slow and powerful inward and downward movement to the gripping jaws so that the threaded neck of the sprinkler head is quickly and strongly 85 gripped thereby.

A movable plunger, such as 27, is preferably mounted within the casing 2 and formed with a yielding socket for contact with the end of the neck or connection of the 90 sprinkler head as by providing an elastic or yielding packing 22 in the upper portion of the protruding plunger head 3. This plunger preferably has a somewhat constricted fluid passage 23 and is provided 95 with suitable packing means, such as the washer 7 engaging the walls 6 of the casing and held in place on the plunger as, for instance, by the nut 25. The supply passage 8 admitting the hydraulic testing fluid to the casing is preferably of larger area or capacity than at least some parts of the fluid passage 23 so that after the sprinkler head has been gripped by the jaws 18 and the testing fluid turned on by the cooperating valve 110

mechanism the pressure rises rapidly in the casing and through its action on the relatively large area plunger forces the plunger upward into firm engagement with the relatively small end of the sprinkler head before sufficient of the testing liquid has passed up through the constricted fluid passage 23 to cause any objectionable leaks around the end of the head. If desired also one or more 10 vent openings 24 may be formed in the upper part of the casing above the plunger to facilitate this upward movement, although this is not in all cases necessary. This upward movement of the plunger takes place 15 rapidly and automatically so that sufficient tightening action takes place practically at once as soon as the testing fluid is turned on so that the head and its fusible link and connections can be thoroughly tested at such 20 hydraulic pressure as is desired, of course any heads which leak under the testing pressure being rejected.

After the head has been tested for the desired length of time the water may be shut 25 off and the pressure in the casing preferably relieved to relieve the upward pressure on the plunger which is thus free to move downward slightly under the resilient action of the parts such as the packing 22 although, 30 if desired, a special releasing spiral spring 29 may in some cases be arranged around the plunger within the casing to facilitate this releasing movement. Then the gripping jaws may be withdrawn by turning the rotary cam 9 to the desired extent which allows the retracting springs to withdraw 35 and simultaneously raise the threaded ends of these gripping jaws which permits the withdrawal of the tested head and the substitution of another head within the jaws 40 which can of course be promptly brought inward and downward by a clamping movement of the cam which thus grips the threaded stem of the succeeding head and 45 simultaneously forces it downward somewhat toward or against the plunger.

This invention has been described in connection with a number of illustrative embodiments, parts, forms, sizes, proportions, 50 materials and arrangements, to the details of which disclosure the invention is not of course to be limited, since what is claimed as new and what is desired to be secured by Letters Patent is set forth in the appended 55 claims.

1. In hydraulic testing devices for testing automatic sprinkler heads or the like, a casing formed with integral brackets and having a groove and a supply passage to 60 supply hydraulic testing fluid to said casing, a series of gripping jaws having cooperating threaded inner ends pivoted to said brackets and having depending jaw arms outside said casing, retracting springs 65 cooperating with said jaw arms to normally

retract said jaws, a rotary cam mounted in said groove in said casing and cooperating with said jaw arms to positively force said jaws inward and downward to engage the threaded stem of a sprinkler head, a plunger vertically slidable in said casing and having a constricted fluid passage of less effective area than said supply passage and having a socket provided with yielding packing on the protruding end of said plunger adjacent said jaws to be forced against the connecting end of the automatic sprinkler engaged by said jaws when the hydraulic testing fluid is admitted to said casing. 80

2. In hydraulic testing devices for testing automatic sprinkler heads or the like, a casing formed with integral brackets and having a supply passage to supply hydraulic testing fluid to said casing, a series of gripping jaws having cooperating threaded inner ends pivoted to said brackets and having depending jaw arms outside said casing, retracting springs cooperating with said jaw arms to normally retract said jaws, a cam 90 cooperating with said jaw arms to positively force said jaws inward and downward to engage the threaded stem of a sprinkler head, a plunger vertically slidable in said casing and having a fluid passage and having a yielding sealing member on the protruding end of said plunger adjacent said jaws to be forced against the connecting end of the automatic sprinkler engaged by said jaws when the hydraulic testing fluid is admitted to said casing. 95

3. In hydraulic testing devices adapted for testing automatic sprinkler heads, a casing having a hydraulic supply passage, two gripping jaws having cooperating threaded inner ends pivoted to said casing and having depending jaw arms adjacent thereto, retracting springs cooperating with jaw arms to normally retract said jaws, cooperating cam means to positively force said jaws inward and downward to engage the threaded stem of a sprinkler head, a plunger 105 slidable in said casing and having a constricted fluid passage of less effective area than said supply passage and having a socket provided with yielding packing on the protruding end of said plunger adjacent said jaws to be forced against the connecting end of the automatic sprinkler engaged by said jaws when the hydraulic testing fluid is admitted to said casing. 115

4. In hydraulic testing devices adapted for testing automatic sprinkler heads, a casing having a hydraulic supply passage, two gripping jaws having cooperating threaded inner ends pivoted to said casing, retracting springs to normally retract said jaws, cooperating cam means to positively force said jaws together to engage the threaded stem of a sprinkler head, a plunger slid- 120

able in said casing and having a constricted fluid passage of less effective area than said supply passage and having a socket provided with yielding packing on the protruding end of said plunger adjacent said jaws to be forced against the connecting end of the automatic sprinkler engaged by said jaws when the hydraulic testing fluid is admitted to said casing.

10 5. In hydraulic testing devices adapted for testing automatic sprinkler heads, a casing having a hydraulic supply passage, two gripping jaws having cooperating inner ends pivoted to said casing, retracting springs to normally retract said jaws, cooperating means to positively force said jaws together to engage the threaded stem of a sprinkler head, a plunger slidable in said casing and having a constricted fluid passage of less effective area than said supply passage and having yielding packing adjacent said jaws to be forced against the connecting end of the automatic sprinkler engaged by said jaws when the hydraulic testing fluid is admitted to said casing.

15 6. In hydraulic testing devices adapted for testing automatic sprinkler heads, a cas-

ing having a supply passage to supply hydraulic testing fluid to said casing, a cooperating series of gripping members, means to manually force said gripping members together and toward said casing to engage a sprinkler head, a plunger slidable in said casing and having a fluid passage and having sealing means adjacent said gripping members to be automatically forced against the connecting end of the automatic sprinkler engaged by said gripping members when the hydraulic testing fluid is admitted to said casing.

20 7. In hydraulic testing devices adapted for testing automatic sprinkler heads, a casing having a supply passage to supply hydraulic testing fluid to said casing, co-operating gripping members, means to force said gripping members together and toward said casing to engage a sprinkler head, a plunger slidable in said casing and having a fluid passage and having sealing means adjacent said gripping members to be forced 45 against the connecting end of the automatic sprinkler engaged by said gripping members.
